PAGE 2

FIG. 4

FIG. 5

FIG. 6

FIG. 7

FIG. 1 is an isometric view of a pneumatic power tool for applying fasteners showing our new design.

FIG. 2 is a side elevational view thereof;

FIG. 3 is a bottom plan view thereof;

FIG. 4 is a top plan view thereof;

FIG. 5 is an elevational view taken from the left side of FIG. 2;

FIG. 6 is a sectional view taken along the section line 6-6 of FIG. 4;

FIG. 7 is an elevational view taken from the right side of FIG. 2.

The side of the fastening device not shown has a similar appearance to the sides disclosed.

We claim:

The ornamental design for a pneumatic power tool for applying fasteners, as shown and described.
